DIRECT WARPING

Ralph H. Balch, Thomas C. Campbell, and James L. Grant, Cumberland, Md., assignors to Celanese Corporation of America, a corporation of Delaware

Application November 30, 1937, Serial No. 177,212

1 Claim. (Cl. 28—40)

- This invention relates to textile machinery, and more particularly to a method of and a machine for the production of warp beams and like packages of yarns or threads.
- 5 It is an object of this invention to produce, in a rapid and expeditious manner, warp beams and like packages of yarn or thread made of or containing fine filaments, particularly artificial silk filaments.
- 10 A further object of this invention is the production of warp beams and like packages of yarn or thread by taking off the yarn or thread from suitable supply packages carried on a support, i. e., a creel, and winding the yarn or thread directly on the beam of the warping machine.

Other objects of this invention, together with certain details of construction and combinations of parts, will be described in the following specification and pointed out in the appended claims.

20 Heretofore in the production of warp beams in the synthetic yarn artificial silk industry, the practice has been on the silk system of warping to build the warp sheet in sections on a warp mill. For example, the yarns were drawn from supply packages on a creel through a condenser reed and a spacer reed onto a large reel rotated by suitable driving mechanism from which it may be disconnected when desired. When the desired lengths of yarn were wound on the warp mill in the form of a narrow band, the reel was released from its driving mechanism and the yarns cut. The bands of yarn were then unwound from the reel onto a bobbin or beam and formed one section of the warp. Two to twenty 30 or more of such sections made up the final warp sheet. On the cotton system of warping which is also in common use in the synthetic yarn industry, the warps are made by winding several hundred threads from cones, spools, or similar packages onto wide beams, or spools called section beams. These beams are mounted on a frame or creel behind the slasher or warp sizing machine and thereon combined into one sheet and wound onto a loom beam forming a part 40 of the sizing operation. With this method a difficult and complicated procedure is necessary in order to obtain an end and end lease. With the equipment heretofore used it was almost impossible to obtain a perfect end and end lease.

50 Furthermore on this cotton system of warping it is also difficult to make warps using two or more types of yarn which must be arranged in a definite warp section pattern. In accordance with the present invention the advantages of the 55 cotton system of warping, particularly its low

cost, is obtained and at the same time all of the advantages inherent to the silk system of warping are retained.

Many attempts have been made to overcome the necessity of forming warps in a plurality of sections. These attempts were not commercially feasible for one reason or another. For example, it has been proposed to use cone creels for avoiding the production of the warp in sections. However, these cone creels, besides being costly 10 and taking up a large amount of floor space, require an additional and expensive processing step, namely the coning of the yarn from the spools.

In accordance with the present invention, there 15 is provided a simple and effective mechanism for forming warp beams of yarns or threads of artificial filaments at less cost than has heretofore been possible and with the requirement of little care or expert attention.

20 In accomplishing the desired result, it is preferred to mount the spools or other supply packages upon a creel arrangement which permits of the handling of the yarns or threads in a novel and extremely practical manner. The creels employed each comprise two sets of banks of supply package holders which are arranged in such a manner that the sheets of yarns or threads coming from each bank leave the creel in relatively closely spaced, substantially parallel planes. As 30 many two-bank creels are employed as are necessary to supply the number of ends required in the warp. Each of the two-bank creels is set at a different level in order that there should be no contact between the ends in the several sheets 35 of yarns or threads coming therefrom. The ends from each bank are led over a roller guide, preferably made up of a series of individual rollers each carrying the yarn or thread from one row of supply packages, then, if desired, through 40 drop wires for operating a suitable stop motion device, and through a reed to the leasing mechanism. The ends are then passed through a standard loom reed, over a guide roll and onto the warp beam.

45 This invention is particularly applicable to the forming of warps from spooled yarns or threads made of or containing fine filaments of silk, reconstituted or regenerated cellulose and/or organic derivatives of cellulose. The organic derivatives of cellulose may be organic esters of cellulose or cellulose ethers. Examples of organic esters of cellulose are cellulose formate, cellulose acetate, cellulose propionate and cellulose butyrate, while examples of cellulose ethers 50

55

are methyl cellulose, ethyl cellulose and benzyl cellulose.

In the accompanying drawing the figure is a perspective view showing the warping machine 5 and creel arrangement of this invention.

The warping machine comprises a main frame 1 having an upright portion 2 at one end thereof. Journalled in suitable bearings on the main frame is the shaft of a warp beam 3 which is rotated 10 in the usual manner, as by means of a motor 4 and variable speed drive 5 through a clutch arrangement 6. The warp beam is also provided with a ratchet wheel and pawl arrangement 7 for maintaining the correct warp tension, and 15 with a braking mechanism 8, as is well understood in the art.

The ends 9 to be wound on the warp beam 3 are drawn from supply packages of any type, such as spools 11 which are arranged in rows on each 20 side or bank of an inverted-V creel 12. In the modification shown, two of such creels are employed. It is to be understood, however, that where a warp having a number of ends greater than the number which can be supplied by two 25 inverted-V creels, which is about 2500, is desired, it is only necessary to add one or more additional creels. Each of these creels is placed at a slightly higher elevation than the one immediately adjacent to the warping machine in 30 order to prevent chafing of the yarns or threads due to contact therebetween.

Each of the banks on each creel is provided with a roller guide 13. Preferably the roller guide is made up of a series of individual rollers each 35 of which is adapted to carry and guide the ends from one vertical row of supply packages 11. The ends 9 pass from rollers 13 through reeds 14 which preferably have glass dents. The sheets of yarns or threads 9 as they leave the reeds 14 40 are substantially parallel and out of contact with each other.

The ends 9 are then passed through a leasing mechanism, generally indicated by reference numeral 15, which is housed in the upright portion 45 2 of the frame 1. The leasing mechanism comprises harness shafts 16 and heddles 17 which may be provided with porcelain, glass or steel eyes, as is well understood in the art.

The harness shafts 16 are raised against the 50 action of springs 18 by means of lines 19 fastened to said harness shafts. These lines are passed over pulleys 21 and are attached to a lever 22 pivoted at 22', which lever is operated by hand lever 23 through connecting rod 24 pivotally attached to levers 22 and 23. The leasing mechanism is adapted to be operated to provide for the crossings or leases in the warp sheet.

All of the warp ends are then passed through a standard loom reed 25, which may be adjustably mounted on the warping machine, and over 60 guide roll 26 which is adapted to rotate and to oscillate or have axial movement, as is well understood in the art. From the guide roll 26, the ends are taken up on warp beam 3. A foot

treadle 27 is provided for mechanical engaging the clutch and for operating the brake. The warping machine may also be provided with a yardage meter 28.

In accordance with the present invention, it is 5 possible to make warps of any desired number of ends with less stretch than heretofore possible. This is due to the fact that the two operations of warping and beaming-down are eliminated by putting the warp on the warp beam in one section. Moreover, putting the warp on the warp beam in one section provides an easy method of inserting an end and end lease which requires 10 less time than heretofore found necessary.

Another advantage of the warping mechanism 15 of this invention is that with the leasing mechanism employed, i. e. harness shafts and heddles, there is less liability of damage being done to the yarns or threads than with the lease rods and reed employed in prior practice. Furthermore, the leasing mechanism of this invention permits of heavier constructions at relatively 20 higher speeds than is practical with the standard leasing devices.

The mechanism described herein performs the 25 desired function in an extremely expeditious and efficient manner, yet it is simple and inexpensive to construct and does not require expert attention to keep the same in running order.

It is to be understood that the foregoing detailed description is merely given by way of illustration and that many variations may be made therein without departing from the spirit of our invention.

Having described our invention, what we desire 35 to secure by Letters Patent is:

Warping apparatus comprising means for driving a warp beam, a plurality of harness shafts disposed between the beam and a yarn creel for guiding yarns to the beam in the form of a plurality of superposed sheets, one sheet for each shaft, and means for raising and lowering said shafts, said means comprising two sets of connections to the shafts so arranged that one operation of the raising and lowering means brings the plurality of warp sheets into two sets between which a lease cord may be inserted, another operation of the raising and lowering means transposes the two sets of warp sheets for the insertion of a second lease cord, and a further operation restores the warp sheets to their original position, the said connections to the shafts being operated by opposite ends of a lever so that an upward movement of shafts connected to one end of the lever is accompanied by a downward movement of shafts connected to the other end of the lever, the lever being provided with means by which it may be rocked to both sides of a mean position for the insertion of the two lease cords and returned to the mean position.
